UNITED STATES PATENT OFFICE.

PEDRO VIDELA, OF SANTIAGO, CHILE.

HYDRAULIC MOTOR.

1,270,674.

Specification of Letters Patent. Patented June 25, 1918.

Application filed October 4, 1916, Serial No. 123,671. Renewed December 1, 1917. Serial No. 205,004.

To all whom it may concern:

Be it known that I, PEDRO VIDELA, a citizen of Chile and a resident of Santiago, in the Province of Santiago, Chile, have invented a new and Improved Hydraulic Motor, of which the following is a full, clear, and exact description.

This invention relates to motors and particularly to a hydraulic motor in which a maximum power is secured from a given quantity of water having a given fall.

The object in view is to provide an improved construction in which a plurality of turbines are connected to a single supply and are acted on successively by the water from said single supply until substantially all of the power has been secured therefrom.

Another object in view is to provide a motor structure with an arrangement of turbines having their casings connected up and stand pipes associated therewith for maintaining a head of water for each turbine from a single source in order to secure a maximum effort from a given supply of water having a given fall.

A still further object of the invention, more specifically, is to produce a turbine in which power may be extracted from the water passing therethrough and the out-go caused to operate one or more succeeding turbines in a similar manner.

In the accompanying drawings:

Figure 1 is a side view of a hydraulic motor disclosing an embodiment of the invention.

Fig. 2 is a side view on an enlarged scale of the lower part of the structure shown in Fig. 1, certain parts being broken away for better disclosing the construction of the casing and turbines arranged therein.

Figure 3 is a sectional view through Fig. 2 on line 3—3, the same being on a slightly reduced scale.

Fig. 4 is a section through Fig. 2 on line 4—4.

Fig. 5 is an end view of the structure shown in Fig. 3, the stand pipes being shown in connection therewith.

Fig. 6 is a detail fragmentary sectional view through the thrust bearing at the outlet pipe.

Referring to the accompanying drawings by numerals, 1 indicates a sluiceway or pipe of any kind for guiding a supply of water

to the receiving box or tank 2, which receiving box or tank is connected with a stand pipe 3 and in free communication therewith so that the stand pipe 3 is always maintained full of water as long as there is a sufficient supply in the tank 2. The pipe 3 extends downwardly and is connected to the casing of the turbine 4, while stand pipes 5, 6, 7 and 8 are connected to their respective turbines 9, 10, 11 and 12. Preferably there are a plurality of turbines and a stand pipe 65 for each one, there being five turbines shown in the drawings, turbine 4 acting as the intake turbine while turbine 12 acts as the outlet which discharges into the outlet pipe 13 and from thence to the discharge pipe 14 which 70 leads to any suitable discharge tank. A shaft 15 is mounted in suitable bearings 16 and 17 and extends through all of the turbines so as to be driven by the various turbines when the device is in operation. The 75 bearing 17 is preferably a thrust bearing, as shown in Fig. 6, in which a removable wearing plate 18 is provided against which the member or foot 19 presses. An adjusting screw 20 presses against the member or foot 80 19 so as to move the shaft 15 longitudinally in one direction whenever desired.

The various turbines 4 and 9 to 12 inclusive, are identically constructed so that a description of turbine 4 will equally apply 85 to the remaining turbines. Referring more particularly to Figs. 2 and 4, the turbine 4 is provided with a casing 21 of any suitable kind which has supporting webs 22 and 23 resting on supporting bars 24 and 25. A discharge outlet 26 is provided at the bottom of casing 21, said outlet being normally closed by a plate 27 which may be held in place by bolts or other means and may be removed when it is desired to clean or secure access 90 to the turbine. Connected to shaft 15 by a key or any other way desired is an impeller or power member 28 which is provided with a plurality of blades 29 formed substantially on the lines of an ogee curve. 95 These blades are inclined in one direction, as shown particularly in Fig. 4, and coact with the standard guide blades 30 on the fixed or stationary rings 31 so that the water may exert its full power on the blades previous 100 to the entrance of the water into the outlet or eye 32 of the impeller, which outlet discharges into the tubular connection 33 (Fig.

2), which tubular connection connects the casing of one motor to the next adjacent motor.

From this it will be seen that the water

5 passing downwardly through pipe 3 will enter casing 21 and entirely surround the impeller 28 at some little distance therefrom and will pass through the valve members 34 mounted on the rotatable rings 35 and be
10 guided by the blades 30 so as to strike blade 29 and will pass between said blades evenly and discharge through the outlet or eye 32. The movement of the impeller 28 is preferably slow so as to absorb more of the energy
15 of the water, but the water passes through the first turbine with a considerable pressure which is not absorbed and enters the casing of the turbine 9 and fills said casing and the stand pipe 5 to practically the center of the glass gage 5'. This causes a reacting pressure on the impeller or rotary member forming part of the turbine 9 so that some additional power will be transmitted to the shaft 15. After the water
20 passes through the turbine 9 it enters the casing of turbine 10 and fills said casing and the stand pipe 6 to the center of the gage 6'. The water acts on the successive turbines in a similar manner so that the
25 head water in stand pipe 7 will be approximately at the center of the gage 7' while the head of the water in the stand pipe 8 will be only slightly above the casing of the turbine. From this it will be observed
30 that the head of water in the respective stand pipes 3 and 5 to 8, inclusive, will be less and less, the head of water in the respective pipes assuming an angle, as indicated by a line drawn through the center
35 of the various gages 3' to 7'.
40

In case it should be desired to shut off any part of the supply of water the rings 35 are rotated somewhat so that the valve members 34 will close to a greater or less extent the openings between the guiding plates 30. This is accomplished by having a link 36 pivotally connected to the rings by a suitable pin 37 preferably passing through both rings, as shown in Fig. 2. Link 36 is also pivotally connected at 38 to the head 39, which head is connected to the threaded bar 40 arranged in the guide 41. The bar 40 extends to a point exteriorly of the casing 1, as shown in Fig. 4, and has a hand wheel 42 mounted thereon, said hand wheel being provided with a hub 43 having a threaded bore fitting the threaded bar 40 so as to move said bar back and forth longitudinally. An annular groove 44 is arranged in the hub 43 and into said groove one or more projections 45 are arranged whereby the wheel 42 together with hub 43 may freely rotate but cannot move longitudinally, thus causing a longitudinal movement of the shaft 40. A hand wheel 42 and

associated parts are connected with each of the motors 9 to 12, inclusive, as well as motor 4, so that the various motors may be adjusted as preferred.

In operation, it is evident that when an ample supply of water is provided in the stand pipe 3 and the water is forced through the impeller or rotary member 28, a certain amount of the energy will be transmitted to shaft 15 while the remaining energy will be dissipated by the water discharged from said impeller unless otherwise utilized. By arranging a plurality of turbines in line and providing casings and stand pipes as described, this unutilized supply of water is caused to operate these additional turbines until the entire full head of water has been fully utilized, which naturally shows a decided increase in power secured from the water over the power secured from a single turbine. It is evident that a larger number or a less number of stand pipes and motors could be associated together for a given supply of water without departing from the spirit of the invention, but by experiment it has been found that five motors will usually absorb all of the energy which will be produced by the fall of water, especially when the parts are arranged as shown, which causes the five turbines together to produce practically three times the power of the first turbine by reason of the distribution of the energy of the water in passing through the entire construction. This construction and arrangement of turbines in sets of a number of units is especially desirable where there is an ample supply of water having a great head or fall, as in such cases it is difficult to secure all the power stored up in the water from a single turbine, but by gradually absorbing the energy by successive turbines substantially any head of water or quantity of water may be utilized to advantage.

What I claim is:

1. A hydraulic motor of the character described, comprising a plurality of independent turbines arranged in a line and in communication so that the discharge from one turbine will pass to the next turbine, stand pipes connected to the casings of the various turbines for maintaining a head of water in the various turbines, means acting as a discharge for the last turbine, and means acting as an inlet member for the first turbine.

2. In a hydraulic motor of the character described, a plurality of turbines provided with independent casings, tubular members connecting the center of the various casings, a stand pipe for each casing in free communication with the upper part of the various casings, a rotor arranged in each casing provided with an eye discharging into the means acting as a communicating member between the casings so that the water

passing through one rotor will be discharged in the next adjacent casing, means for directing water to the first stand pipe, and means for directing the water away from 5 the last casing.

3. In a hydraulic motor of the character described, a plurality of casings arranged in line, tubular members connecting the centers of said casings together, a stand pipe 10 for each casing in free communication therewith, a rotor partially filling each casing and

arranged so that the eye will discharge in said tubular members, a shaft extending through said casings connected with said rotors for receiving power therefrom, means 15 for leading water from the last casing, and means for directing water to the first stand pipe whereby the various casings will be filled with water and the stand pipes filled to different heights for producing different 20 heads of water for the successive rotors.

PEDRO VIDELA.
